UNITED STATES PATENT OFFICE.

JOHN M. GARDNER AND SAMUEL H. GARDNER, OF NEW YORK, N. Y.

BOX OR BASKET.

SPECIFICATION forming part of Letters Patent No. 252,027, dated January 10, 1882.

Application filed June 25, 1881. (No model.)

To all whom it may concern:

Be it known that we, JOHN M. GARDNER and SAMUEL H. GARDNER, citizens of the United States, residing at New York, in the county and State of New York, have invented certain new and useful Improvements in Boxes and Baskets; and we do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 Our invention relates to baskets, boxes, or the like, formed of laced veneers or similar material; and the novelty consists in the construction and arrangement of parts, as will be more fully hereinafter set forth, and specifically pointed out in the claims.

20 The object of the invention is to provide a convenient and ornamental box or basket, the parts of which are held in operative position by cords or lacings, and which may be readily taken apart and compactly folded for transportation or storage; and to this end I employ the materials herein described and the construction shown in the accompanying drawings, which form a part of this specification, and in which—

25 Figure 1 is a top plan view, with a portion of the sides displaced, and with a part of the bottom broken to show the several thicknesses; Fig. 2, a side elevation, partially broken away; Fig. 3, a detail view.

30 In carrying out the invention I take preferably two or more thicknesses of veneer, cross-grained, and properly secured together to form one section. Near the side edges of each section are formed a series of perforations adapted to receive lacings, and in the bottom of each section, upon the same edge, is formed a kerf or recess to receive studs or lugs upon the bottom. These boxes or baskets are 35 formed triangular, hexagonal, or polygonal, and the bottoms are of similar form, the corners having projections, as shown.

Referring to the drawings, A represents the bottom, of polygonal form, and provided at each corner with a stud, pin, or other projection, d, which is received in the recesses b of the sections B. As many sections are used in the formation of a basket as there are sides to the bottom, and the sections are secured together by laces C, which operate through the perforations c near the contiguous edges of the sections, the bottom being held in place by the projections d resting in the recesses b.

40 The sections may be ornamented at will, and the laces be of such contrasting or gay colors as will best please the fancy.

To take this basket apart it is only necessary to undo one of the laces, when the bottom becomes disengaged and the sides pack together very closely.

45 As shown, the side sections are variously perforated, and different ornamentations may be made by tastefully weaving through such perforations various-colored worsteds or the like.

50 Having thus described our invention, what we claim as new, and desire to secure by Letters Patent, is—

1. A box or basket formed of a polygonal bottom having projections at three or more of its corners, and a number of recessed and perforated sections corresponding to the number of sides upon the bottom, said sections receiving the said projections, and the whole being secured together by laces, substantially as 55 specified.

2. The bottom A, having projections d, combined with the series of sections B, having perforations c and recesses b, and with the laces C, as and for the purposes set forth.

60 50 In testimony whereof we affix our signatures in presence of two witnesses.

JOHN M. GARDNER.
SAMUEL H. GARDNER.
